(57) **CLAIM**

The ornamental design for a combined lid and container as shown and described.

DESCRIPTION

FIG. 1 is a top perspective view of a combined lid and container, shown without the container for ease of illustration, showing our new design;

FIG. 2 is a top plan view thereof, shown without the container for ease of illustration;

FIG. 3 is a left side elevation view thereof, shown without the container for ease of illustration, the right side elevation view being the same;

FIG. 4 is a front elevation view thereof, shown without the container for ease of illustration, the rear elevation view being the same;

FIG. 5 is a bottom plan view thereof shown without the container for ease of illustration;

FIG. 6 is an exploded top perspective view thereof;

FIG. 7 is a top perspective thereof, shown without the lid for ease of illustration;

FIG. 8 is a top plan view thereof, shown without the lid for ease of illustration;

FIG. 9 is a front elevation view thereof, shown without the lid for ease of illustration, the rear elevation view being the same;

FIG. 10 is a left side elevation view thereof, shown without the lid for ease of illustration, the right side elevation view being the same; and,

FIG. 11 is a bottom plan view thereof, shown without the lid for ease of illustration.

The broken lines in the figures illustrate the portions of the combined lid and container and form no part of the claimed design.

The combined lid and container has been shown with symbolic breaks. The appearance of any portion of the article between the break lines forms no part of the claimed design.
